UNITED STATES PATENT OFFICE.

JOHN TOBIN, OF NEWARK, NEW JERSEY.

HANDLE.

SPECIFICATION forming part of Letters Patent No. 399,170, dated March 5, 1889.

Application filed January 12, 1888. Serial No. 260,537. (No model.)

To all whom it may concern:

Be it known that I, JOHN TOBIN, a citizen of the United States, residing at Newark, in the county of Essex and State of New Jersey, have invented new and useful Improvements in Handles, of which the following is a specification.

This invention has for its object to provide a novel handle especially designed for coffee-pots and like articles; and it consists in the features of construction hereinafter described and claimed, reference being made to the accompanying drawings, illustrating the invention, in which—

15 Figure 1 represents a side elevation of a coffee-pot provided with my improved handle. Fig. 2 is a longitudinal section of the handle detached, said figure being drawn to a larger scale than the preceding figure. Fig. 3 is a 20 similar section taken in a plane at right angles to the plane of Fig. 2. Fig. 4 is a longitudinal section of a modification.

Similar letters indicate corresponding parts.

In the drawings, the letter A designates the 25 body of the handle, which is made in any convenient form and of any suitable material, a poor conductor of heat—such as wood—being preferable. In said body A is a longitudinal bore, *a*, and a transverse bore, *b*, which 30 bores intersect each other and are intended to receive the handle-sections B and C.

In the handle-section C is formed an internal thread, *c*, which receives an external thread, *d*, on the end of the handle-section B, 35 whereby the two handle-sections are connected to each other in the interior of the body A and are held firmly to said body.

In Fig. 4 I have shown the handle-section C as being provided with an external thread, *d'*, and the handle-section B with an internal 40 thread, *c'*.

The exterior ends of the handle-sections B and C can be secured to the pot in any suit-

able way—for instance, as shown in Fig. 1, by the use of attaching-plates *e* and *f*, which 45 are soldered to said sections and to the pot.

The body A is at its upper end formed into a solid closed head, which can be ornamented in any fashion desired, and the main bore *a* and transverse counterbore *b* intersect or 50 join at the inner side of the closed head. The sections B and C are composed of wires or rods circular in cross-section, and, as shown, the inner end of one has a screw-thread which directly screws into a screw-socket formed in 55 the inner end of the other, while the outer end of each wire or rod section is bent into a vertical plane, or approximately so, so that they can be soldered to the aforesaid plates *ef*.

A handle constructed as hereinbefore described can be rapidly and cheaply produced, and presents a neat and ornamental appearance.

What I claim as new, and desire to secure by Letters Patent, is—

A handle for coffee-pots and other articles, consisting of a body, A, having a solid closed head, a longitudinal bore extending into the body to the closed head thereof, a counterbore, *b*, extending laterally through the body 70 at right angles to the main bore below the head, and the handle-sections B and C, extending, respectively, into the said bores, one having formed directly in its extremity a transverse screw-socket, into which directly 75 screws the screw-threaded end of the other, the outer ends of said sections being bent and adapted to be attached to the article, substantially as shown and described.

In testimony whereof I have hereunto set 80 my hand and seal in the presence of two subscribing witnesses.

JOHN TOBIN. [L. s.]
